HERBERT I. HANSEN AND JOHN A. HINRICHES, OF PATERSON, NEW JERSEY; SAID HINRICHES ASSIGNOR TO SAID HANSEN

WARP LET-OFF ATTACHMENT

Application filed September 19, 1929. Serial No. 393,755.

This invention appertains to looms, and more particularly to a novel attachment for looms designed to automatically and positively release the warp from the warp beam or roll with every pick of the loom, thereby preventing such defects which appear in the weaving of cloth incident to the warp not being fed properly.

In looms now generally in use, the warp beam or roll is provided with a flange on each end of the same on which there is a rope wound around a number of times and held tight by cast iron loom weights. These weights are slipped on the rope as required by the weaver; different kinds of silk and other cloth have different amounts of weights so as to keep the warp tight, thereby making the loom pull the silk or woolen against the friction of the rope. The main difficulty with the use of the rope has been that due to the climatic conditions, the rope would have a tendency to stick on the warp beam or roll and instead of moving a certain amount for each pick of the loom, it would hold for two or three picks, then release and jump a large distance all at once, which will show a mark in the finished cloth, due to the releasing of the tension on the warp. Certain devices have been formulated with the end in view to prevent the friction rope from sticking on the flanges of the warp beam or roll, but these devices have not been positive in their operation and are not practical and will not operate satisfactorily for any length of time.

There are any number of other types of let-off motions on the market at the present time, all attempting to eliminate the rope, but with very little success, because the price of these articles is prohibitive and entirely too complicated.

It is, therefore, one of the primary objects of our invention to provide a positive means actuated from a working part of the loom for disturbing the tension of the friction rope on each pick of the loom and thereby insuring a positive release of the warp from the warp beam regularly and in the exact length required.

Another important object of our inven-

tion is the provision of a tap rod slidable on the frame of the loom actuated preferably by the lay beam with means operated by the tap rod for disturbing the tension of the friction rope, which makes it impossible for the rope to stick at any time regardless of climate or wear of the rope.

Another important object of our invention is the provision of a novel ratchet device arranged between the tap rod and the clamp for engaging the rope, which permits these parts to be adjusted so as to overcome the difference in the length of the rope due to the stretch of the same. This is especially desirable when new rope is installed and which has considerable stretch.

A further important object of our invention is the provision of novel means for setting the tap rod whereby the tap from the lay beam will only be transferred to the rope to the extent of the amount of pre-set of said tap rod.

A still further object of our invention is to provide a device of the above character which can be incorporated with a loom of conventional character without any change in design thereof, the attachment being essentially simple and durable in construction and one which can be manufactured at a very low cost.

With these and other objects in view, the invention consists in the novel construction, arrangement and formation of parts as will be hereinafter more specifically described, claimed and illustrated in the accompanying drawings, in which drawings:

Figure 1 is a side elevation of our improved device showing the same applied to a conventional loom, the loom being shown fragmentarily and in light lines and in dash lines;

Figure 2 is an end elevation of our novel device showing the same engaging the friction rope of the warp beam or roll;

Figure 3 is a detail sectional view illustrating the connection between the tap rod and the clamping means for engaging the friction rope;

Figure 4 is a detail perspective view illustrating one of the holding and guide brackets for the tap rod, and

trating the means of connection of one part of the ratchet device to the friction rope.

Referring to the drawings in detail, where-in similar reference characters designate corresponding parts throughout the several views, the letter A generally indicates our improved attachment for the loom B. The loom B can be of any preferred character or type and includes the usual frame 10 having the lay beam 11 actuated in the ordinary manner and the warp beam or roll 12 for receiving the warp of the fabric being woven. The warp roll or beam in accordance with the usual construction, is flanged to provide a drum, pulley or the like 13, around which is coiled the friction rope 14. The opposite ends of the friction rope receive respectively loom weights 15 and 16, which are slipped on the rope as required by the weaver, different kinds of fabric requiring different amounts of weight. It is well to note in the present instance that the weight 16 can be eliminated and the ends of the rope which ordinarily receive these weights can be tied to the loom frame and this practice is common in the weaving art. Our device which will be presently described is particularly adapted to the friction ropes when the same are tied to the loom 10 and we desire to stress this point in view of the fact that certain other structures within our knowledge, which attempt to disturb the tension of the friction rope without positive means will not function where one end of the rope is tied. Also our attachment is particularly adapted to looms for weaving broad silk, but it is to be understood that the attachment is adaptable for other kinds of fabric being woven.

Our improved attachment comprises a tap rod 20 which extends longitudinally of the loom frame, and this tap rod includes the front rod section 21 and the back rod section 22, and these sections 21 and 22 are adjustably connected by means of a turnbuckle 23. A jam nut 24 can be employed for holding the turnbuckle nut against accidental movement. The tap rod is slidably mounted in suitable brackets 25 and 26 carried by the frame of the loom and each of these brackets include attaching plates 27 bolted or otherwise secured to the loom frame, and an outwardly extending supporting rod 28. This supporting rod 28 has adjustably mounted thereon a slide bracket 29 which in turn adjustably carries a depending supporting arm 30. The lower end of each arm 30 carries a cap 31 having adjustably mounted thereon for swinging movement the collar or sleeve 32 through which extends the tap rod. The forward end of the tap rod section 21 is provided with a hammer cap 33 which can be provided with a wear and cushioning pad 34. This pad or plug 34 can be made of raw hide and the hammer cap 33 with its plug is arranged in the path of the lay beam 11 so that the rod 21 will be tapped

by the lay beam on each pick of the loom. It is to be noted that the brackets are arranged respectively adjacent to the front and rear of the loom so that the tap rod 20 will be effectively supported in its sliding movement. The brackets can be made adjustable so that the device can be readily placed on different types and makes of looms. The outer end of the back rod section 22 has secured thereto the ratchet shoe 35, the side walls 36 of which form guides for engaging the opposite sides of the arcuate rack or ratchet bar 37 which is adapted to engage over the friction rope. The opposite side of the arcuate rack or ratchet bar 37 carries guide wheels 38 for engaging the flanges or sides of the drum or pulley of the warp beam or roll.

The central portion of the arcuate rack or ratchet bar 37 is provided with a depending ear 39, the opposite sides of which are adapted to be engaged by clamping jaws 40 and 41. These clamping jaws are adapted to grip one convolution of the friction rope 14. An adjusting bolt 42 extends through the clamping jaws 40 and 41 and through the ear 39 and forms means for bringing the jaws in firm clamping contact with the convolution of the friction rope 14. Thus, it can be seen that the arcuate rack or ratchet bar 37 is firmly clamped with the friction rope. The ratchet shoe 35 pivotally supports a weighted dog or dogs 43 having a depending tooth 44 for engaging an adjacent tooth of the arcuate rack or rack bar 37.

From the description so far it can be seen that our device operates as follows:—On each pick of the loom the lay beam 11 will push the tap rod 21, consequently sliding the same in the collar 32 and this motion will be transferred to the rope clamp through the ratchet device. This makes it impossible for the rope to stick regardless of climate or wear of the rope. Should the rope stretch at any time, the ratchet or rack bar 37 will simply move with the rope and the weighted dogs will still be enabled to engage an adjacent ratchet tooth, thereby eliminating all difficulty in the changing of position of the rope clamp due to the stretch of the rope.

Another important feature of our invention is the provision of means for setting the tap rod so that the lay of the loom will transfer the tap to the rope at the proper time and only to the extent of the amount of the preset. This setting mechanism embodies spaced collars 45 and 46 which are keyed or otherwise secured in spaced relation to the tap rod 20 on opposite sides of the guide sleeves 32 of the bracket 26. An expansion spring 47 is placed about the tap rod and engages the guide sleeve 32 and the collar 46. It is obvious that this spring functions to return the tap rod to its normal position, at each operation thereof by the lay, and that by adjusting the position of the collars 45 and 46

the movement of the tap rod 20 and the tension of the spring can be regulated.

Changes in details may be made without departing from the spirit or the scope of this invention, but what we claim as new is:

1. A loom attachment comprising in combination with the warp roll or beam, a rope coiled about said beam, a clamp carried by one of the convolutions of the rope, a longitudinally movable tap rod positively actuated on each pick of the loom for engaging said clamp to disturb the tension of the rope, and a ratchet device between the clamp and tap rod.
2. A loom attachment comprising in combination with the warp roll or beam, a tension rope looped about said beam and a lay beam, a longitudinally movable tap rod disposed in the path of the lay beam and actuated thereby, and means for transferring the movement of the tap rod to the rope.

3. A loom attachment comprising in combination with the warp roll or beam, a tension rope looped about said beam and a lay beam, a longitudinally movable tap rod disposed in the path of the lay beam and actuated thereby, means for transferring the movement of the tap rod to the rope, and means for initially adjusting the tap rod relative to the lay beam.

4. A loom attachment comprising in combination with the loom frame, a warp roll, and a lay beam, a tensioned rope looped about the said warp roll, guide brackets secured to the loom frame, a tap rod slidably mounted in the guide brackets and disposed in the path of the lay beam and adapted to be actuated thereby, and means for transmitting the motion of the tap rod to the tensioned rope.

5. A loom attachment comprising in combination with the loom frame, a lay beam and a warp roll, a weighted rope looped about the end of the warp roll, guide brackets secured to the loom frame, a tap rod slidably mounted in the brackets and disposed in the path of the lay beam and adapted to be actuated thereby, means for transmitting the movement of the tap rod to the rope, stop collars adjustably mounted on the tap rod and installed on opposite sides of one of the brackets, and an expansion spring coiled about the tap rod and engaging one of the collars and one of the brackets.

6. A loom attachment comprising in combination with the lay beam, the warp roll or beam, a rope coiled about said warp beam or roll, a tap rod disposed in the path of the lay beam and actuated thereby, an arcuate ratchet bar arranged on one of the convolutions of the rope, means for securing the arcuate ratchet bar to said convolution of the rope, a ratchet shoe carried by the tap rod and slidable over the ratchet bar, and a

weighted dog for engaging the teeth of the ratchet bar.

7. As a new article of manufacture, a let-off attachment for looms comprising a pair of adjustable brackets, a tap rod slidable in said brackets, a hammer cap carried by one end of the rod, a ratchet shoe carried by the opposite end of the rod, an arcuate rack bar, a rope clamp carried by the rack bar, means for adjusting the active length of the tap rod, adjustable collars secured to the tap rod on each side of one of the brackets, and a coil spring and tap rod disposed between one of the collars and the adjacent bracket.

In testimony whereof we affix our signatures.

HERBERT I. HANSEN.
JOHN A. HINRICHSEN.
